FIG.1

FIG.2

FIG.3

FIG. 5

FIG. 4

FIG. 6

FIG. 1 is a perspective view of a combined scabbard and knife sharpener showing my new design;

FIG. 2 is a side elevation view and the opposite side view is identical thereto;

FIG. 3 is a top plan view and a bottom plan view is an unornamented polygonal configuration;

FIG. 4 is a front elevation;

FIG. 5 is a perspective view, similar to FIG. 1, the three forwardly and upwardly projecting knife supporting elements in their downwardly depressed condition;

FIG. 6 is a side elevation, similar to FIG. 2, showing and similarly illustrates the three forwardly and upwardly projecting knife supporting elements in their downwardly depressed condition.

The characterizing features of my design reside in the configuration and appearance of the front panel portion and the knife supporting elements projecting therefrom.

I claim:

The ornamental design for a combined scabbard and knife sharpener, as shown and described.
